GAS GENERATING APPARATUS

Roy M. Mead, Asheville, N. C., assignor to
 American Gas Service Company, Lima, Ohio,
 a corporation of Ohio

Application March 5, 1938, Serial No. 194,186

6 Claims. (Cl. 62—1)

This invention relates to an apparatus for generating gas, particularly fuel gas, in localities where central station distribution facilities do not exist.

5 The distribution of liquefied gas to isolated consumers has now become an accepted practice. Hydrocarbon gases, such as propane and butane, may be readily liquefied and vaporize at relatively low temperatures, providing a reliable 10 source of fuel gas. The gas in liquefied form is usually delivered to a storage tank on the customer's premises from time to time by tank cars or trucks. The storage tanks are usually buried in the ground, but may also be disposed on the 15 surface. In either case, the liquefied gas vaporizes and builds up a substantial pressure in the storage tank by absorbing heat from the surrounding medium. In order to avoid seasonal temperature changes, the tanks are usually 20 buried below the frost line.

The rate of vaporization of the liquefied gas depends on the amount of heat absorbed. When a storage tank of conventional design is substantially full of liquefied gas, the body of liquid absorbs heat from the ground through practically 25 the entire surface area of the tank. When the liquid level falls due to consumption of the gas, the surface of the body of fluid exposed to heat absorption is correspondingly reduced. This decreases the rate of evaporation 30 and lowers the pressure of the gas in the tank.

I have invented an apparatus for maintaining liquefied gas contained in an underground storage tank, in contact with a greater portion 35 of the surface area of the tank than would be covered by the liquid at its natural level determined by the volume of liquid in the tank. Expressed in slightly different language, the invention makes it possible to cause a portion 40 of the liquefied gas in the storage tank to be disposed in heat-exchange contact with a portion of the tank wall above the level at which the volume of liquid in the tank would otherwise stand.

45 In a preferred form of the invention, I provide a tank having a double wall extending over at least a portion of its surface providing storage and vaporizing chambers. Filling connections extend through the inner wall and a gas offtake is connected to the outer wall or to a dome communicating therewith. I also provide a connection between the space within the inner wall and that between the inner wall and the outer wall, whereby liquefied gas may flow under 50 the vapor pressure existing in the space within the inner wall, from said space into the space between the walls. The liquid filling the inter-wall space absorbs heat from an area of the surrounding earth considerably greater than that 55 to which liquid would be exposed if permitted

to find its natural level in the inner tank. Further details of the apparatus and its operation will be described herebelow with reference to the accompanying drawing, the single figure of which is a largely diagrammatic view showing in section a buried tank embodying the invention and the filling and delivery connections thereto.

5 Referring in detail to the drawing, the illustrated embodiment of the invention comprises a 10 tank 18, having an inner container 11, defining a storage space indicated generally at 12. An outer wall or shell 13 partly surrounds the container 11 and is spaced therefrom defining an intermediate vaporizing space 14. I prefer to leave a portion of the surface of the container 11 exposed to the surrounding medium as indicated at 15. The shell or outer wall 13 is preferably provided with a dome 16 defining a space 17 for the accumulation of gas.

15 Filling pipes 18 extend downwardly from the surface of the ground through the outer shell 13 and the wall of the inner container 11 and are provided with valves 19. A gas offtake 20 extends upwardly from the dome 16 and has a 25 main control valve 21 connected therein.

A pipe 22 extends upwardly from substantially 30 the bottom of the space 12 through the wall of the container 11 to a point about midway of the height of the dome 16. The purpose of this connection will be explained later. A vent and overflow pipe 23 extends downwardly through the shell 13 and the wall of the container 11 from a point in the dome 16 at or slightly below 35 the level of the top of the pipe 22. The pipe 23 has a seat 24 at the upper end thereof cooperating with a valve 25. The valve is carried on a pivoted arm 26 adapted to be actuated by a float 27 when the liquid rises in the dome 16 to the level indicated at 28.

40 In explaining the operation of the invention, it will be assumed, first, that the double wall tank is being filled for the first time and contains air only. The tank is filled by connecting a tank truck or other portable container having 45 a supply of liquefied gas therein to one of the pipes 18, and opening the valve 19 therein. The valve 19 in the other pipe 18 is opened to vent the air content as the container 11 is filled. The valve 21 should be closed while filling the container. When the container 11 has been substantially filled, both valves 19 are closed. Vaporization of the liquefied gas commences immediately since the boiling point of the liquefied gas usually employed is lower than the normal 50 temperature of the earth below the frost line. At 30° F., for example, certain liquefied fuel gases have a vapor pressure of four or five pounds per square inch above that of the atmosphere. If the container 11 is initially filled to a level 55

60

- such as that indicated at 28, the pressure in the space above the surface of the liquid will build up as soon as valves 18 are closed, to a value sufficient to cause liquid to flow upwardly through the pipe 22 and overflow into the space 14. It will be understood that the initial evolution of vapor in the space above the liquid in the container 11 is caused by heat absorbed largely through the portion 15 of the container wall.
- 10 In order to cause liquid to flow upwardly through the pipe 22, it is obvious that a pressure differential must exist between the container 11 and the space 14. Since the latter initially contains air at atmospheric pressure, the required differential pressure is created very promptly by absorption of heat through the portion 15 of the container wall.
- 15

When the space 14 has been filled, the liquid therein is subject to direct absorption of heat from the surrounding earth through the wall thereof. Evolution of vapor from the body of liquid in the space 14 thus proceeds even more rapidly than that within the container 11. This causes the pressure in the dome 16 to build up promptly. Fuel gas in the form of vapor may now be drawn from the dome 16 by opening the valve 21. The system should be purged of air before being connected to burners.

Assuming that before the valve 21 is opened, the temperatures and pressures in the spaces 12 and 17 have become equalized, flow of liquid upwardly through the pipe 22 will cease. When the valve 21 is opened, however, the resulting outflow of gas from the dome 16 causes a drop in the pressure and temperature in the space 17, and if the amount of gas withdrawn is sufficient, the differential pressure necessary to cause resumption of the liquid flow upwardly through the pipe 22 will be established. If the gas is withdrawn from the dome 16 at a rate such as to cause the liquid to rise to the level 28, the float valve 25 will be opened to connect the space above the liquid in the container 11 directly to the dome, thus equalizing the pressure throughout the system and preventing further flow of liquid upwardly through the pipe 22.

The float valve 25 and vent pipe 23 may be omitted if the rate of withdrawing gas from the dome is so limited as to prevent the liquid level rising to the level of the connection of the pipe 20 therewith. With the float valve and vent pipe, it is impossible for the liquid to rise above the level 28, regardless of the rate of withdrawal of gas.

It will be apparent that the apparatus shown maintains a supply of liquid in the space 14 at all times, thus insuring that the liquid covers a greater portion of the wall of the container than would be the case if it were allowed to seek its natural level. As already explained, when no gas is withdrawn from the dome over a considerable period, the temperature and pressure conditions throughout all portions of the system become equalized. On withdrawal of gas, however, the cooling and reduction in pressure within the space 17 provides the differential necessary to cause liquid to flow upwardly through the pipe 22 until temperature and pressure conditions are again equalized or the valve 25 is opened to effect this result.

Refilling of container 11 after it has been placed in operation is accomplished by connecting one pipe 18 to the discharge port of the tank truck and by connecting the other pipe 18 to the tank truck above the level of the liquid therein. The

liquid in the tank truck thus flows into the container 11 under the pressure existing therein, making it unnecessary to close the valve 21 or shut off burners connected to the system while refilling the container.

It will be readily appreciated that the invention provides a source of fuel gas, the pressure of which does not vary so widely as it does in a system comprising an ordinary tank, wherein the area of the tank wall covered by the liquid for heat absorption from the earth decreases as the level of the liquid falls as a result of consumption of gas. The invention thus provides a more satisfactory and reliable source of fuel gas for isolated consumers than has heretofore been available.

I have illustrated and described herein only one embodiment of the invention, but it will be understood that numerous changes in the construction and arrangement shown may be made without departing from the spirit of the invention or the scope of the appended claims.

I claim:

1. Gas-generating apparatus comprising a container adapted to receive liquefied gas, a shell extending about at least a portion of said container, means whereby liquefied gas may be delivered to the container, means whereby liquefied gas from said container flows into the space between the container and shell, and a valve operable when the liquid in said space reaches a predetermined level to vent the container to said space.

2. A fuel-supply system comprising a storage tank, means whereby said tank may be filled at intervals with liquid combustible which vaporizes at atmospheric temperatures, an offtake for vapor evolving from said liquid, a shell overlying at least a portion of said tank and a pipe extending downwardly into the tank to a point near the bottom thereof for conducting liquid from said tank to the space between the tank and shell when the differential between the vapor pressures in the tank and said space increases sufficiently.

3. A fuel-supply system comprising a liquid storage and evaporating tank having an outer wall in heat-exchange contact with a surrounding medium, means whereby said tank may be filled at intervals with liquid combustible which vaporizes at atmospheric temperatures, an offtake for vapor evolving from said liquid, and means whereby the pressure of said vapor maintains a portion of said liquid in contact with the tank wall above the level of the main body of the liquid in said tank as said level falls because of the removal of vapor from the tank.

4. Apparatus as defined by claim 3 characterized by said tank including a shell overlying at least a portion thereof, and means for delivering liquid from the tank to the shell, said vapor offtake communicating with said shell.

5. Apparatus as defined by claim 3 characterized by said tank including a shell overlying at least a portion thereof, means for conveying liquid from the tank to the shell, and a collecting dome on said shell, said vapor offtake being connected to said dome.

6. Apparatus as defined by claim 3 characterized by said tank including a shell overlying at least a portion thereof, and said means including a connection from the tank adapted to convey liquid therefrom to the space between the tank and shell when the vapor pressure in said space decreases sufficiently below that in said tank.

ROY M. MEAD.
